Application May 16, 1950, Serial No. 162,224

4 Claims. (Cl. 101—292)

1

The present invention relates to a printing machine especially useful in printing information on a moving strip which is fed through the machine and severed thereby to produce individually printed labels. In large stores many labels or price tags are required in connection with the goods being merchandised. The labels normally carry a standard imprint of the store's name or trade-mark and, in addition, an individual imprint to identify the several items of merchandise. These items may vary from time to time, and the problem is presented of imprinting the labels accordingly. For purposes of appearance, these labels or price tags are printed. However, unless these price tags or labels are printed in large quantities, the price per unit is relatively high. On the other hand, when large quantities of labels or price tags are printed, a great deal of money is invested in the labels or price tags themselves, particularly when, for example, there may be a label or price tag for a given commodity such as, for example, a can of tomatoes at different prices at which it is thought such a can would sell at different times over a period of months.

It is therefore an object of the present invention to provide an improved printing machine characterized by its simplicity, smallness and inexpensiveness for use in individual stores, whereby the storekeeper may print his labels or price tags as required.

Another object of the present invention is to provide an improved printing machine of this character having as important features thereof improved means whereby the machine may be conveniently adjusted to print and cut different sized labels or price tags.

Another object of the present invention is to provide a printing machine of this character which has a printing plate associated with an inking pad, a paper feeding mechanism and a paper cutting mechanism, there being provided independent means whereby the printing platform, pad, paper feeding and paper cutting mechanisms may be adjusted in a simple and expeditious manner.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view in side elevation, partly in 55

2

section, of a printing machine embodying features of the present invention.

Figure 2 is a sectional view taken substantially on the line 2—2 of Figure 5.

5 Figure 3 is a view in elevation of a portion of the paper cutting mechanism taken substantially on the line 3—3 indicated in Figure 5, but with the mechanism in a different operating position.

Figure 4 is a view similar to Figure 2 but with 10 the inking plate in a different position.

Figures 5 and 6 are sectional views taken substantially on the lines 5—5 and 6—6 of Figure 1.

Figure 7 is a perspective view of a portion of the paper cutting mechanism.

15 Figure 8 is a plan view of the paper supplied to the machine and indicates the region at which the paper, after printing, is severed.

Figure 9 is a view taken substantially on the line 9—9 of Figure 1, and

20 Figure 10 is a perspective view of the plate holder partly fragmented to show the prongs insertable in the plate to aid in maintaining the same in position.

The machine functions to intermittently feed 25 paper 10 from the supply reel 11, past the printing station 12 (Figure 1), over the paper driving drum 13, and then to the cutting station 14, at which successive sections of the paper are severed and fall into the discharge chute 15.

30 The power for performing these three functions, namely, paper feeding, printing and severing, is obtained from the electric driving motor 16, which is mounted on the side 17 of a framework. The motor output shaft 18 has mounted thereon a V-pulley 19 as well as an auxiliary knob 20 for manually turning the shaft 18 when desired, for example, in adjusting various mechanisms in the machine. Belt 22 passing over pulley 19 serves to drive the pulley 24 mounted on the input shaft 25 of the reduction gear, the housing 27 of which is mounted on the stationary shelf 28 with the two oppositely extending output shafts 30, 31 (Figure 5) driving crank members 32, 33, respectively. Each of these cranks

35 40 45 serves to impart generally a longitudinal movement to corresponding ones of pairs of rods 34, 35 and 36, 37. As will be described in detail hereinafter, the rods 34, 35 actuate the guillotine type of cutting knife 39, and the rods 36, 37 serve to move the printing plate 40 (Figures 5, 2 and 4) cyclically from its printing position shown in Figures 5 and 2 to a position abutting the inking pad 42, whereby ink may be transferred from the pad 42 onto the paper 10.

50 55 In addition, the crank 32, upon rotation, im-

parts a reciprocatory movement to the rod (Figures 5 and 1) which serves to intermittently drive the paper feeding drum 13 over which the paper 10 is fed, with the conical shaped and equally spaced circumferential projections 45 projecting through the equally and centrally spaced apertures 10A (Figure 8) in the paper 10.

The paper 10 as originally supplied may have the name of the store imprinted thereon, such as "John Doe Co.," and the machine may function to print descriptive material in successive rectangular printed blocks 10B information such as, for example, "Tomatoes 15¢." This printing, of course, is all accomplished at station 12 (Figure 1) by the automatically inked printing plate 40 (Figure 2). Such printing is accomplished when the paper tape or strip 10 is stationary; and, at the same time, the individual printed sections are being severed at station 14 (Figure 1). Since the printing and cutting of the paper tape is accomplished when the tape is stationary, an intermittent movement of the tape 10 is necessitated.

Such intermittent movement of the tape 10 is produced by the paper feeding mechanism, which includes a pawl and ratchet arrangement 46, 47 (Figures 1 and 6). The pawl 46 is pivotally mounted on the arm 50 which is pin-connected at any one of the predeterminedly spaced apertures portions 51, 53 to one end of the rod 43. This arm 50 is mounted for pivotal movement on the stationary shaft 54 (Figures 1 and 6), which also rotatably supports the drum 13 and which is affixed, at its other end, in the frame 55.

The ratchet 47 is adjustably positioned on the end wall of the drum 13 by releasable bolts 56 which extend through adjustment slots in the ratchet member 47, and which are screw threadedly received in such end wall of the drum 13. This adjustment allows changes in the lengthwise position of the printed matter on the labels. The pawl member is constantly urged upwardly against the ratchet member 47 by the coil tension spring 57, having one of its ends affixed to the arm 50 and the other one of its ends affixed to the pawl 46. Thus, when and as the rod 43 is reciprocated in response to rotation of the crank member 32, the paper driving drum 13 will be intermittently moved in a counterclockwise direction, as indicated by the arrow 58 in Figure 1. The ratchet 47 is adjusted to produce movement of the paper after the printing and cutting operations have been accomplished respectively at stations 12 and 14 (Figure 1), as mentioned above. The length of paper moved upon one reciprocation of the rod 43, which corresponds to the distance between printings, may be adjusted as previously indicated by pin-connecting the end of the rod 43 to the arm 50 at any one of the desired apertured portions 51, 53. In general, such paper in its travel around the drum 13 is guided to some extent by the pair of parallelly extending stationary guide rods 88, 89, which, as shown in Figure 6, are supported on stationary arms 90 extending from the stationary frame 55 and serve to maintain the paper against the drum to thereby prevent the drum pins 45 from becoming disengaged from the paper apertured portions 10A.

At the printing station 12 the holder 59, releasably holding the plate 40, is alternately moved from its printing position adjacent the adjustable paper platform 60 to its inking position in contact with the inking pad 42, and then returned

to its printing position, all during one rotation of the crank 32. The manner in which the plate holder 59 is moved is indicated in Figure 4.

Specifically, the holder 59 has a rectangular opening to snugly and releasably receive the plate 40 of elastic material with a thin sheet of backing material 61 disposed between the plate 40 and holder 59 as described hereinafter in connection with Figure 10. This holder 59, as shown in Figures 5 and 2, has a pair of bifurcated arms 63, 64 extending therefrom. A pair of stationary pivot pins 65, 66 is disposed, at all times, within the slotted portion defined by the bifurcated arms 63, 64, respectively, as indicated in Figure 2. These pivot pins 65, 66, each project inwardly from a U-shaped supporting frame 64 which is of sheet material and formed at the U-bend thereof to provide a generally rectangular dish 64A for frictionally receiving the ink pad 42 with the sheet metal member 68 glued to pad 42 between the pad 42 and the holder, the sheet metal member 68 being conveniently provided with a tab 68A which conveniently extends outwardly to facilitate removal of the pad 42 with the sheet metal 68 which partially embraces such pad. Also, such member 68 may have a plurality of beads or dimples 68B extending outwardly therefrom engaging with corresponding cooperating reentrant portions in dish 64A to frictionally and releasably support such assembled pad 42 and strip 68, as a unit, within the dish 64A. This U-shaped frame 67, in turn, is bolted to the adjustable frame member 69.

Also passing through the slotted portion of the bifurcated arms 63, 64 is the rod 78, which has its opposite ends passing through the corresponding cam slots 71, 72 and through the lost motion slots 73, 74 in the upper ends of the actuating rods 36, 37. The upper ends of these rods 36, 37 are guided for generally vertical movement by providing, at their upper ends, a pair of projections 36A, 36A and 37A, 37A, which respectively cooperate with the corresponding vertical slots 75, 75 and 76, 76 in opposite legs of the frame 67.

Thus, upon upward movement of rods 36 in Figure 1, the member 70, traveling in the lost motion slot 73 and cam slot 71, causes the printing plate 40 to gradually turn, as indicated in Figure 4. The plate holder 59 pivots about the stationary pivot 66 during such movement to such an extent that at the upper end of travel of the rod 36 the printing surface of plate 40 is pressed into contact with the inking pad 42. Upon subsequent downward movement of the rod 36 the plate holder 59 retraces its path, and at the lower end of movement of rod 36 the plate 40 is pressed into printing engagement with the paper 10 resting on the adjustable platform 60.

A feature of the present invention is that the inking pad 42, as well as the printing platform 60, may be adjusted independently of each other. For that purpose, both the printing platform 60 and frame member 69 are pivotally mounted on the stationary axle 77, which has its opposite ends affixed to the stationary framework. The forward ends of these members 69, 60 may be adjusted in elevation independently of each other upon movement of the corresponding adjustment screws 78, 79. Both of these screws 78, 79 are screw threadedly received in the stationary frame member 80. The bolt 78 passes through an enlarged opening in the member 69, so that the coil compression spring 81 may be adjusted to different compressed conditions. On the other hand,

the bolt 78 has its upwardly protruding end engaging the bottom face of the platform 60 and is maintained in locked position by the lock nut 82. It is observed that the spring 81 serves not only to maintain the frame 69 in adjusted locked position, but also imparts some resiliency in the printing plate holding structure. This is of importance and absorbs some of the energy of the moving arms 36, 37 and actuated printing holder 59 when and as these members are moving to their lowermost positions, corresponding to engagement of the printing plate 40 with the paper 10.

Thus the paper is initially printed, using the mechanism described above, and then passes over the intermittently driven feeding roller 13 before it passes to the cutting station 14.

Cutting of the paper is accomplished with a mechanism perhaps best seen in Figures 2, 7 and 3. A feature of the cutting mechanism is that it is adjustable to automatically cut off the paper at a predetermined selected position between or at the paper holes 10A (Figure 8), this adjustment being independent of any one of the other adjustments described above.

The plane of movement of the guillotine type of knife 39 is at an angle inclined somewhat with respect to the vertical, as indicated in Figure 2, and serves to cut off successive sections of paper 10, which is fed from the roller 13 into the throat defined by the spaced sheet metal members 85, 86 after being deflected by the stationary deflecting plate 87. The paper guides 85, 86, as well as the cutting knife 39, are mounted on an adjustably positioned subframe which has the general reference numeral 91.

This subframe 91 comprises a pair of upstanding parallel arms 92, 93, each of which are pivotally mounted on corresponding circular shoulders 27A, 27B on the gear box 27. These arms 92, 93 have secured thereto the paper guide members 85, 86, it being noted that the screw threaded aperture 94 in Figure 7 is utilized to fasten the paper guide plate 85 (not shown in Figure 7) which cooperates with the plate 86. These pivotally mounted arms 92, 93 have extending upwardly therefrom the arms 95, 96, the upper ends of which are interconnected by the rod 98 which, as shown in Figures 2 and 3, has a screw threaded aperture for receiving the adjustment bolt 99. This adjustment bolt 99 passes through an enlarged opening in the stationary frame member 100 (Figure 2), so that rotation of the bolt 99 results in pivotal adjusted movement of the subframe 91, which may be maintained in adjusted position upon fastening the lock nut 101. This lock nut 101 cooperates with the nut 102, which forms a seat for one end of the coil compression spring 104, the other end of the spring 104 abutting against the washer 105 which bears against the stationary frame member 100.

The spring 104 thus serves not only as a part of the locking mechanism, but also imparts some resiliency to the pivoted subframe 91 in any one of its predetermined adjusted positions.

The arms 92, 93 also carry upwardly inclined arms 106, 107, respectively, which support a pivot rod 108. Mounted on this rod 108 is a pair of pivotally mounted arms 109, 110 through which the knife actuating rod 111 passes. This rod 111 pivotally mounts the knife 39 which has a pair of hubs 39A, 39B mounted thereon. Thus, the knife 39 is pivotally mounted on the rod 111, but with a coil tension spring 112 having one of its ends affixed to the knife 39 and the other one of its

ends affixed to the arm 96, biasing the knife 39 in a clockwise direction in Figure 7, with the lower portion of the knife 39 abutting an edge of the paper guide 86. The paper guide 86 thus serves also as a stop for pivotal movement of the knife 39, which otherwise would exist. The knife 39 is provided with a downwardly extending projection 39C which engages the edge of the guide 86 when the knife is in a raised position, to allow paper to move under the knife 39 for subsequent severing.

It is thus observed that the paper is sheared between the knife 39 and the forward edge of the paper guide 86. In order to withstand the relatively large forces to which the paper guide 86 is subjected, the guide 86 is reinforced by a pair of transversely extending frame members 113, 114 (Figure 2), which are affixed to the side walls or arms 92, 93. The knife 39 is moved upwardly and downwardly as a result of the pivotal movement imparted to shaft 111 by the pair of rods 34, 35 which have lost motion slots in their upper ends through which the ends of shaft 111 project. These lost motion slots in the rods 34, 35 are disposed and are of such an extent that the knife 39 is moved downwardly at a time when the intermittently moving paper is stationary and substantially contemporaneous with printing of the paper at station 12. Such downward or cutting movement of the knife 39 causes the tension spring 112 to be stressed a greater amount, and subsequently, when and as the rod members 34, 35 are moved upwardly, the knife 39 follows the motion of the arms until the knife 39 abuts the horizontal extensions 95A, 96A of arms 95, 96, respectively, which thus serve the purpose of a stop.

After the paper is severed it drops into the chute or stationary bin 15 formed of sheet metal 40 and fastened to the upper surface of the gear housing 27, as indicated in Figure 1.

It is observed that the longitudinal axis of the output shaft 30 of the gear reduction unit 27 is coaxial with the pivoting axis of the subframe 91 (Figure 7) which carries the movable knife 39, and that the particular region at which the paper is severed is controlled, as mentioned above, upon adjustment of the screw 99. However, it is noted, as explained above, that the particular length of paper severed may be controlled by utilizing any one of the two apertured portions 51, 53 (Figure 1) in the arm of the paper feeding mechanism.

The plate holder 59, perhaps best seen in Figure 10, allows quick attachment and detachment of the printing plate 40. The holder 59, as seen in Figure 2, is of sheet metal stock and comprises generally an inverted pan or dish with a pair of integrally formed prongs or tongues 200, 201 extending into the dish for insertion in cooperating apertured portions in the plate 40. The other side wall of the holder 59 has mounted thereon a double leaf spring 202 which is fastened, as for example, by means of a rivet 203 at a point intermediate its ends to a side wall of the holder 59, with the ends of such spring 202 projecting through apertures 204, 205 in such side wall for resilient engagement with the printing plate disposed in the holder 59.

In inserting a printing plate 40 in the holder 59, initially the apertured end of such plate is inserted such that the prongs 200, 201 enter such apertured portions. Then the plate is pivoted upwardly about such prongs 200, 201 as a pivot point to bring the opposite end of the printing

plate into resilient engagement with the ends of the leaf spring 202, such opposite end of the plate being provided with indented portions to receive the ends of spring 202. The leaf spring 202 thus cooperates with the adjacent end of the printing plate and comprises a detent means for resiliently maintaining the plate in the holder 59. When it is desired to remove the printing plate from the holder 59, the person merely inserts his finger through the finger hole 206 in the base plate 207 of the holder so as to force such plate out of resilient engagement with the leaf spring 202.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

We claim:

1. In a printing machine of the character described, a frame supporting a generally horizontally extending shaft, a printing platform pivotally mounted on said shaft, an inking pad, a member pivotally mounted on said shaft, said inking pad being mounted on said member, adjusting means mounted on said frame and engaging the free end of said platform, and second adjusting means between said frame and the free end of said member to adjust the position of said pad, said second adjusting means comprising resilient means between said frame and said member.

2. In a printing machine of the character described, a frame, a shaft mounted on said frame, a printing platform pivotally mounted on said shaft, an inking pad, an inking pad supporting member pivotally mounted on said shaft with the inking pad disposed above and facing the printing platform, a printing plate, a guide structure supporting said plate and arranged to guide said plate from a position adjacent the printing platform to a position adjacent the inking pad, adjustable supporting means arranged to position

one end of said printing platform at different elevations, second adjusting means arranged to adjust the height of said inking pad supporting member, said adjusting means including a resilient connection between said inking pad supporting member and said frame, a power driven shaft mounted on said frame, and means connected to said power driven shaft for moving said printing plate from a position adjacent said printing platform to a position adjacent said inking pad.

3. In a printing machine of the character described, a frame, a printing platform pivotally mounted on said frame about a first axis, means for adjusting the free end of said printing platform, a printing plate, an arm pivoted about said first axis, means supporting said printing plate on said arm, and means adjustably and resiliently supporting the free end of said arm.

4. In a printing machine of the character described, a frame, an adjustable printing platform an inking pad, an arm mounting said inking pad, a shaft mounted on said frame, said arm and platform being mounted for pivotal movement about the axis of said shaft, and independently operable adjusting means for adjusting the free ends of said platform and arm with respect to said frame.
